US00D583956S

(12) **United States Design Patent**
Chang et al.

(10) **Patent No.:** **US D583,956 S**
(b4) **Date of Patent:** **** Dec. 30, 2008**

(54) **ORTHOTIC DEVICE**

(75) Inventors: **Julia Chang**, Los Angeles, CA (US);
Stacy Wyatt, Camarillo, CA (US);
William K. Arnold, Woodland Hills, CA
(US)

(73) Assignee: **Ossur, hf**, Reykjavik (IS)

(**) Term: **14 Years**

(21) Appl. No.: **29/290,505**

(22) Filed: **Dec. 11, 2007**

(51) **LOC (8) Cl.** **24-01**

(52) **U.S. Cl.** **D24/192**

(58) **Field of Classification Search** **D24/169, D24/188-192; 602/4-8, 13, 16, 20-23, 27-29, 602/65; D29/120.1, 121.2, 122; D2/946; 128/877-879, 881, 882, DIG. 20; 36/54, 36/88, 110, 117.1, 118.6, 119.1**

(57) **CLAIM**

The ornamental design for an orthotic device, as shown and described.

DESCRIPTION

FIG. 1 is a perspective view of an orthotic device showing our design.

FIG. 2 is a side elevational view of the device of FIG. 1.

FIG. 3 is a top plan view of the device of FIG. 1.

FIG. 4 is a bottom plan view of the device of FIG. 1.

FIG. 5 is a front elevational view of the device of FIG. 1; and, FIG. 6 is a rear elevational view of the device of FIG. 1.

The broken lines illustrate unclaimed portions of the orthotic device.
